(57) CLAIM

An ornamental design for an ornamental stuffed cloth ball, as shown and described.

DESCRIPTION

FIG. 1 is a front view of the completed cloth-covered, stuffed ball showing a sample of a human head on the outer surface of the ball.

FIG. 2 is a side view of the cloth-covered, stuffed ball showing a sample of a human head on the outer surface of the ball; and,

FIG. 3 is a perspective view of the cloth-covered, stuffed ball showing a sample of a human head on the outer surface of the ball.

The broken lines in the Figures indicate are for illustrative purposes only and forms no part of the claimed design.
